ATTORNEY S.

UNITED STATES PATENT OFFICE.

ADOLPH W. MORITZ, OF SOUTHFIELD, NEW YORK.

BOTTLE.

SPECIFICATION forming part of Letters Patent No. 579,651, dated March 30, 1897.

Application filed April 25, 1896. Serial No. 589,184. (No model.)

To all whom it may concern:

Be it known that I, ADOLPH W. MORITZ, a citizen of the United States, and a resident of the town of Southfield, in the county of Rich-
mond and State of New York, have invented 5 certain new and useful Improvements in Bottles, of which the following is a specification, reference being had to the accompanying drawings, forming a part thereof, in which
10 similar letters of reference indicate corresponding parts.

This invention relates to bottles, jugs, jars, and similar vessels; and the object thereof is to provide a vessel of this class with a neck 15 attachment whereby when the vessel has once been filled and the attachment applied the vessel may be emptied of its contents, but cannot be refilled or reused.

The invention is fully disclosed in the following specification, of which the accompanying drawings form a part, in which—

Figure 1 is a central vertical section of the upper part of a bottle or other vessel provided with my improved attachment, and Fig. 2 a 25 side view thereof.

In the practice of my invention I provide a bottle or vessel having a neck A, which is preferably provided with an annular shoulder or projection a, and the inner walls of 30 which are provided above said annular shoulder or projection with notches or recesses a², or the annular groove may be substituted for said notches or recesses, if desired. I also provide a cap or cover which consists of a 35 tubular casing B, the lower end of which is adapted to inclose the upper end of the neck and to rest on the annular shoulder a, and the upper end of which is conical in form, as shown at b, and provided with a central open- 40 ing b² at the top thereof.

Secured within the cap or cover B or the body portion thereof is a partition-plate D, the central portion of which is curved upwardly, so as to form a conical upwardly-directed extension d, the upper end of which is open and provided with a valve G, which is provided with a depending rod g, the lower end of which is provided with a weight g². 45

The upper side of the valve G is preferably 50 flat and the lower side thereof conical in form, and secured within the cap or cover and centrally of the upper part thereof is a tube H,

the lower end of which is larger than the upper end, and said lower end is secured to the partition-plate D, and mounted therein above the valve G is a cap h, which is hollow and slightly conical in form and the base of which is directed downwardly, and the tube H is provided with a partition-plate h², in which is formed a central opening through which 60 passes a bolt K, provided with a button or head k and on which is mounted a spring L, the lower end of which bears on the partition-plate h² and the upper end of which bears on a shoulder or projection k², formed on the bolt K, and on one side of the tube H is an inwardly-directed shoulder or projection h³. 65

The cap or cover B or the body portion thereof is provided with a number of perforations or openings b⁴, which are formed 70 therein above the partition-plate D, and at one side of the bottom of the tube H is an opening M, with which a tube m communicates, which passes upwardly and outwardly through the conical portion of the cap or cover, 75 as shown at m².

Secured to the lower side of the plate or partition D are depending spring-arms O, the lower ends of which are provided with outwardly-directed projections or heads O², 80 which are adapted to operate in connection with the notches or recesses a², so as to securely connect the attachment with the neck of the vessel, and the bolt K is adapted to be depressed, so that the cap h will rest on the 85 valve G, in which position the bolt K may be turned so that the shoulder or projection k² will rest beneath the shoulder or projection h³ on the tube H and hold the bolt in the depressed position, and the bottle will be sealed 90 by the pressure of the cap h on the valve G.

The operation will be readily understood from the foregoing description when taken in connection with the accompanying drawings and the following statement thereof. 95

In this class of devices the bottle or vessel must first be filled before the neck attachment is applied, and the bottle or vessel provided with the neck A having been filled with the desired contents the neck attachment is secured thereto, as will be readily understood, by forcing the lower end of the body portion B downwardly over the upper end of the neck, in which operation the spring-arms O 100

pass inside of the neck and the heads or projections O^2 enter the notches or recesses a^2 and securely hold the attachment in place and prevent the removal thereof. The outer 5 end of the tube m may be closed by a cork or plug, if necessary, and when it is desired to empty the bottle or vessel or discharge a portion of its contents said plug or stopper is removed and the bolt K is turned so as to 10 release the shoulder or projection h^3 , after which the cap h will be raised by the spring L , and when the bottle or vessel is inverted or tilted the contents thereof will flow out around the valve, which will leave its seat 15 under the action of gravity and the pressure of liquids within the bottle or vessel, and the latter will flow out into the lower end of the tube H and through the tube m , as will be readily understood, and this operation may 20 be continued or repeated until the bottle or vessel is entirely empty.

If an attempt be made to refill the bottle or vessel by pouring liquids thereinto, the valve G will at once be reseated and no liquids 25 can enter the bottle, and said liquids will also flow out through the side ports or openings b^4 in the cap or cover. The depending rod g and the weight g^2 serve to assist in this operation of the valve, and said operation 30 of the valve will be the same in any position in which the bottle or vessel may be held in an attempt to pour liquids thereinto, and said valve may also be made to act as a float-valve, in which event no liquids could be forced into 35 the bottle, and if an attempt be made to force liquids into the bottle the same would pass out through the lower end of the tube H and the side ports or openings b^4 , it being observed that the lower end of the tube H is 40 also perforated, so as to correspond with the side ports or openings b^4 .

This device is simple in construction and operation and perfectly adapted to accomplish the result for which it is intended, while 45 being also comparatively inexpensive.

Having fully described my invention, I claim as new and desire to secure by Letters Patent—

1. The combination with a bottle or other 50 vessel provided with a neck, of a cap or cover comprising a tubular body portion, and a top, said body portion being provided with a partition-plate at or near the middle thereof, the central portion of which is directed upwardly 55 to form a conical extension which is open at the top, a valve adapted to be seated on said conical extension and having a depending rod secured thereto, a weight mounted on the lower end of said rod, and said valve adapted 60 to close the port or opening through said extension, said cover being provided with side ports or openings above said partition-plate, and means for holding the valve in place, substantially as shown and described.

2. The combination with a bottle or other 65 vessel provided with a neck, of a cap or cover comprising a tubular body portion, and a top,

said body portion being provided with a partition-plate at or near the middle thereof, the central portion of which is directed upwardly 70 to form a conical extension which is open at the top, a valve adapted to be seated on said conical extension, and to close the port or opening therethrough, said cover being provided with side ports or openings above said partition-plate, and means for holding the valve in place, consisting of a vertically-movable cap which is mounted in the lower end of a central tube which is secured within the cap or cover, and the lower end of which rests upon 80 said partition-plate, and means for operating said vertically-movable cap, substantially as shown and described.

3. The combination with a bottle or other vessel provided with a neck, of a cap or cover 85 comprising a tubular body portion, and a top, said body portion being provided with a partition-plate at or near the middle thereof, the central portion of which is directed upwardly to form a conical extension which is open at 90 the top, a valve adapted to be seated on said conical extension, and to close the port or opening therethrough, said cover being provided with side ports or openings above said partition-plate, and means for holding the 95 valve in place, consisting of a vertically-movable cap which is mounted in the lower end of a central tube which is secured within the cap or cover, and the lower end of which rests upon said partition-plate, and means for operating 100 said vertically-movable cap, consisting of a rod which passes through the top of the cap or cover, and which is connected therewith, substantially as shown and described.

4. The combination with a bottle or other 105 vessel provided with a neck, of a cap or cover comprising a tubular body portion, and a top, said body portion being provided with a partition-plate at or near the middle thereof, the central portion of which is directed upwardly 110 to form a conical extension which is open at the top, a valve adapted to be seated on said conical extension, and to close the port or opening therethrough, said cover being provided with side ports or openings above said 115 partition-plate, and means for holding the valve in place, consisting of a vertically-movable cap which is mounted in the lower end of a central tube which is secured within said cap or cover, and the lower end of which rests upon said partition-plate, and means for operating 120 said vertically-movable cap, consisting of a rod which passes through the top of the cap or cover, and which is connected therewith, and a tube which communicates with the 125 lower end of the central tube, and the end of which extends upwardly and outwardly through the top of the cap or cover, substantially as shown and described.

5. An attachment for the neck of the bottle 130 or other vessel, consisting of a cap or cover, the body portion of which is tubular in form, and provided with a top, said body portion being provided with a partition-plate at or

near the middle thereof, the central portion of which is upwardly curved to form a conical extension the upper end of which is open, a valve adapted to close the passage through 5 said conical extension, and provided with a depending weighted rod, a central tube placed within the cap or cover, and secured to the upper side of said partition-plate, a vertically-movable cap placed therein over the valve, 10 and means for operating the same, said central tube being larger at the base than at the upper end, and provided with a tube, which communicates with the lower end thereof, and

which passes outwardly through the cap or cover, and said central tube and the body portion of the cap or cover being also perforated, 15 substantially as shown and described.

In testimony that I claim the foregoing as my invention I have signed my name, in presence of the subscribing witnesses, this 3d day 20 of April, 1896.

ADOLPH W. MORITZ.
